UNITED STATES PATENT OFFICE.

FREDERICK E. TOWNSEND, OF NEW YORK, N. Y., ASSIGNOR, BY DIRECT AND MESNE ASSIGNMENTS, OF ONE-HALF TO DOUGLAS SPRAGUE, OF MOUNT VERNON, NEW YORK, AND ONE-HALF TO HENRY C. KARLSON, OF HASBROUCK HEIGHTS, NEW JERSEY.

WINDING IMPLEMENT.

1,397,022.

Specification of Letters Patent. Patented Nov. 15, 1921.

Application filed December 31, 1917, Serial No. 209,744. Renewed February 16, 1921. Serial No. 445,447.

To all whom it may concern:

Be it known that I, FREDERICK E. TOWNSEND, a citizen of the United States, and a resident of the borough of Manhattan, in the county, city, and State of New York, have invented certain new and useful Improvements in Winding Implements, of which the following is a specification.

This invention relates to devices employed for winding woolen and other yarns into balls of convenient size for knitting or kindred purposes.

One object of the invention is to produce an improved implement of the character described, affording a simple means wherewith the yarn can be wound rapidly, evenly, and with uniform firmness throughout, so that the ball formed thereby may retain its shape until it is all used, or nearly so, without unraveling or becoming tangled.

Another object is the production of an implement of the type set forth which shall leave both ends of the yarn free as it is being formed into a ball, so as to permit the unwinding thereof either from within or from without, as may be desired.

A further object is to provide a self-contained implement of the class mentioned, the parts whereof may be stowed one into another whenever the implement is not being used for winding.

Other objects and advantages of the invention will become apparent as the specification proceeds.

With the aforesaid objects in view, the invention consists of the improvements, novel construction, arrangements and combinations of parts hereinafter described, defined in the subjoined claims, and illustrated in their preferred embodiments by the annexed drawing, wherein like elements are designated by the same reference characters throughout the different views.

In the said drawing:—

Figure I is a front elevation of this improved implement set in operative position, the view showing how the winding of the yarn is started;

Fig. II is a similar elevation, representing the implement with a ball of yarn formed thereon;

Fig. III is a top plan view of the implement, without the yarn;

Fig. IV is a bottom end view of the main member of the implement;

55

Fig. V is a side view of the same member;

Fig. VI is a longitudinal section running along the central plane of the said member positioned as in the preceding figure; and

Fig. VII is a side view of an auxiliary member included in the implement.

Referring to the above mentioned views for a detailed description of the invention, the numerals "1" and "2" denote two members of which the implement is composed. 65 These members are adapted to be put and held together in the shape of a cross, as appears in Figs. I, II and III. The main member 1, previously referred to, constitutes the standard of the cross, while the auxiliary member 2, also before alluded to, forms the arms thereof. The two members make up together the entire implement, in the embodiment of the invention herein exemplified.

75

Provision is made to attach the two said members, removably, one to the other, without nails or other fastenings. This is accomplished by boring a hole, as 3, across the upper portion of the main member, as illustrated in Figs. V and VI, and passing therethrough the auxiliary member 2, by a single sliding movement in the direction of its own axis, in a manner that is well understood. The hole 3, which constitutes a socket, is 80 made relatively small, to insure a tight fit therein, and in order to provide for the ready insertion of the transverse member 2, the said hole is supplemented by incisions 4 and 5, extending on opposite sides thereof, longitudinally of the upright member 1. The latter-named member, which may be made of wood or other suitable material, has sufficient resilience ordinarily first to admit and then to clasp the member 2 in the hole 3, and 85 maintains it there in a firm position, due to the coöperation of the slits or incisions 4 and 5.

90

A notch 6 is made, preferably in the main member 1 and at the bottom end thereof, to 100 provide a holding means for one terminal of the yarn, represented by A. As seen in Figs. V and VI, the notch 6 may be V-shaped, so that the yarn can be quickly caught and held therein, after the manner illustrated in Figs. 105 I and II.

When not in use, the auxiliary member 2 may be placed inside the main member 1, as represented in Fig. VI, for which purpose the main member is formed with a chamber 7, extending axially thereof, from the notch 6 to a point near the lower incision 4, previously mentioned. The slotted end of the main member may be capped or plugged over the outer extremity of the auxiliary member, if so desired, so that the two members will be kept safely one within the other.

In winding the yarn upon the implement, one end thereof is first inserted and stayed in the notch 6 of the main member, as before stated. Thence the yarn is carried up and looped once around either arm of the auxiliary member, as indicated at B, Fig. I. From the looped arm, the yarn is passed diagonally across the main member and over the opposite arm of the auxiliary member, as shown at C, after which the yarn is brought again under the first-named arm, as at D. Then, a few turns of the yarn may be taken diagonally of the main member and alternately over and under the opposite arms of the auxiliary member to form one or more layers, as suggested in Fig. II. By preference, the main member is revolved slowly as the winding continues, and the yarn crossed while so doing, in order to produce oppositely disposed layers, as at E, F, in the latter named figure. When the winding is completed, the last end of the yarn is placed under an outside strand of the external layer, either E or F, as the case may be, and the ball of yarn can be removed as an entirety from the implement. This is effected, first by drawing out the auxiliary member 2; secondly, by unhitching the end A; and thirdly, by pulling out the main member. After the two said members have been withdrawn, the loose end A is pushed into the hole produced by the main member, from which place it can be retracted, and the whole of the yarn unwound in knitting, gradually as required.

While a certain preferred embodiment of this implement has been shown and described, it will be understood that changes in the form, arrangements, sizes, proportions and details thereof may be made without departing from the scope of the invention as defined by the appended claims.

Having described my invention what I desire to secure by Letters Patent, and claim is:

1. An implement of the character described, comprising a main member having a transversely disposed socket and one of its ends extended to serve as a handle portion, and an auxiliary member removably seated across said main member, by sliding it endwise through said socket the arrangement being such that after the yarn has been wound around the inner corners between the arms of the implement said auxiliary mem-

ber may be detached from the main member while the ball of yarn formed over both members is in place, whereafter the main member can be removed from the completed ball of yarn.

2. An implement of the character described, comprising a main member having a part thereof adapted for grasping by one hand when using the implement and being further provided with a transverse seat, and an auxiliary member removably engaging the seat in said main member, the intersecting portions of said members being designed to receive the yarn wound crisscross therearound by the other hand, said auxiliary member being completely separable from the main member by a single movement in the direction of its own axis while the yarn is in place on both members, whereafter the completed ball of yarn may be removed by sliding it off either end of the member first above named.

3. A winding implement comprising a pair of members held together crosswise, the main member of said pair constituting the standard of the cross and having a transverse opening, the other member of the pair being of smaller diameter and adapted to be passed through said opening thereby forming the arms of the cross, said implement in use being adapted to be grasped by its standard with one hand and the yarn wound in alternate diagonal layers over and under the arms thereof by the other hand, said smaller member being separable from said main member while the ball of yarn formed thereon is in place, whereby the latter may subsequently be removed endwise from the member last named.

4. A winding implement comprising a main member and an auxiliary member together forming a cross, one part of said main member being adapted for grasping by one hand when the implement is in use and yarn is wound diagonally over and under the arms thereof by the other hand, the main member having a transverse opening with an incision extending therefrom, said auxiliary member being frictionally held in said opening through co-action with its said incision so as to be readily separable from the main member while the ball of yarn formed thereon is in place, whereby the latter may be afterward slid off the end of the last mentioned member.

5. A winding implement comprising a main member having a transverse opening and an auxiliary member passing removably through the latter, said members forming together a dismountable cross, said main member being adapted for grasping by one hand when the implement is in use and yarn wound in diagonal layers over and under the arms thereof by the other hand, said auxiliary member being separable from the

main member while a ball of yarn formed thereon is in place, whereby the ball may be afterward slid endwise off the last mentioned member, the latter being provided with a 5 longitudinal recess extending from one end thereof in proximity to said transverse opening and adapted to house the auxiliary member when not in use.

6. An implement of the character described, comprising a main member including a part suitable for grasping by one hand when using the implement, said main member being provided with a seat spaced from said grasping part, an auxiliary member re- 10

15 movably engaging said seat and extending

on both sides of the main member in order to present opposed crotches adapted to receive the yarn wound thereover in crossed directions by the other hand, the arrangement being such that said auxiliary member 20 is first detachable from the main member and the latter is subsequently removable from the completed ball of yarn, and means formed near one end of the main member wherein one terminal of the yarn may be 25 stayed when commencing the winding, which terminal permits the unwinding of the ball of yarn from the interior thereof without unwinding its exterior.

FREDERICK E. TOWNSEND.
